Des. 571

Everard Bolton, of Northern Liberties, Pa
Assignor to
Abram Box & Joseph Box, of Philadelphia, Pa.
Letters Patent No. 571. Dated June 21st 1853.

The schedule referred to in these Letters Patent and making part of the same

To all whom it may concern:

Be it Known that I, Everard Bolton, of Northern Liberties, in the County of Philadelphia, and State of Pennsylvania, have invented or produced a new and original design in Cook Stoves called

"The Triumph Complete,"

and I do hereby declare that the following is a full and complete description of the same; reference being had to the annexed drawings forming part of this specification, in which Figure 1. is a side elevation of the stove.

Figure 2, is a front elevation, and

Figure 3, a rear elevation -

On the several figures similar letters of reference denote the same part of the stove and design.

Symmetrical ornaments have but one half the details of the design shown, the remainder being drawn in outline.

Upon each of the side plates A, are the oven and feed doors B and C, both of which are raised above the plate A, and surrounded by a bead; the panel of the former is ornamented in bas-relief by the figure a, having the foliage b and c, issuing from it, the foliage c, bearing the spherical projections d, the whole having the configuration set forth in figure 1. The door C, is ornamented in bas-relief by the figure f, with the foliage g, and projections h, all arranged as set forth in figure 1.

Upon the lower front plate P, are the doors D, the panels of which are surrounded by the mouldings E, and ornamented in bas-relief by the figure k, foliage i, and spherical projections l, arranged and forming the ornament set forth in figure 2.

The feed door F is surrounded by the moulding m, and ornamented in bas-relief by the elliptical figure n, oak leaves p, and acorns o, arranged and combined as shown in figure 2.

Exterior to the doors D, upon the front plate P, are the ornaments in bas-relief G, composed of the foliage q, and projections r, arranged as shown in figure 2.

Between the extremities of the feed opening and the front plate P, are the curved surfaces H, ornamented in bas-relief by the figures I, having the configuration and arrangement set forth in figure 2.

The upper front plate K, is surrounded by the bead I, and embellished in bas-relief by the figure s, with the foliage t, sweeping from it, the latter bearing the globular projections u, the whole arranged and having the configuration set forth in figure 2. Upon the plate K, and beneath the ornament is the inscription "Triumph ornate Patented 1853 by A & J Cox, Phila $\frac{da}{n}$ " in raised capitals and numerals.

The back plate B, of the stove is ornamented by the tablet S raised, by the moulding x, and bearing the bead y, arranged as shown in figure 3.

One of the side plates A, instead of the door C, has a panel

Ms. 571

180

What I claim as my invention or production and desire to secure by Letters Patent, is

The ornamental designs in bas relief upon the doors B, C, D, and E, and plates A, P, K, and R, of the configuration and arrangement set forth in this specification and the annexed drawings, forming a new and original design for the Cook stove called the "Triumph Complete".

In testimony whereof, I have hereunto signed my name before two subscribing Witnesses.
